United States Patent Office.

DAVID STUART AND LEWIS BRIDGE, OF PHILADELPHIA, PENNSYLVANIA, ASSIGNEES
TO DAVID STUART AND RICHARD PETERSON, OF SAME PLACE.

Design No. 3,911, dated March 15, 1870; antedated March 1, 1870.

DESIGN FOR COOKING-STOVE.

The Schedule referred to in these Letters Patent and making part of the same.

We, DAVID STUART and LEWIS BRIDGE, both of Philadelphia, county of Philadelphia, State of Pennsylvania, have invented or produced a new and original Design for a Cooking-Stove, of which the following is a specification.

The figure in the accompanying drawing represents in perspective the body of a cooking-stove, which we have termed the "Sunnyside Cook," and which is made in accordance with our design.

This design relates to the general shape and configuration of a cooking-stove, irrespective of any ornamentation of the plates, doors, and panels of the same.

General Description.

A is the lower front portion of the stove, beyond which projects the portion B containing the fire-chamber, this portion being surmounted by a plate, D, which extends beyond the front plate of the portion B, and over the main body E of the stove, to the point where the latter is elevated, this elevated portion of the stove being marked F, and being surmounted with a plate, G.

The hearth-plate H projects from the front A of the stove at the lower portion of the projecting portion B,

and at the rear of the stove is the projection I, the bottom of which is curved, as shown.

The dotted lines in the top plates represent boiler-holes, which may be arranged in the manner shown, and the dotted lines in the front and side plates represent doors and panels, the arrangement of which, however, as well as the ornamentation of the plates of the stove, constitutes no part of our present design.

The edges of the plates G, D, H, and I are rounded, as shown in the drawing, and the front and the side plates, near the lower edges, are curved slightly outward, and rounded.

Below the hearth-plate H is a rectangular box, having inclined sides.

Claim.

The design for a cook-stove, as represented in and by the accompanying drawing.

In testimony whereof we have signed our names to this specification in the presence of two subscribing witnesses.

DAVID STUART.
LEWIS BRIDGE.
